UNITED STATES PATENT OFFICE

EDWIN S. PETERSEN, OF CHICAGO HEIGHTS, ILLINOIS, ASSIGNOR, BY MESNE ASSIGNMENTS, TO THE PATENT AND LICENSING CORPORATION, OF BOSTON, MASSACHUSETTS, A CORPORATION OF MASSACHUSETTS

MECHANISM FOR SYNCHRONIZING THE FEEDING AND CUTTING OF SHEET MATERIAL

Application filed December 1, 1927. Serial No. 237,110.

This invention relates to a mechanism for synchronizing the feeding and cutting of sheet material so that the cuts will coincide with some predetermined portion of a recurring 5 ring pattern on the sheet. While the apparatus is suitable for a wide variety of sheet materials, one more particular use for which it is especially adapted is illustrated in the roofing industry where strip shingles and the like 10 are successively cut from an advancing sheet of roofing material. For various reasons, it is desirable in the formation of strip shingles which are provided with slots defining shingle-simulating tabs, to form such slots in 15 the sheet of roofing material before cutting the sheet into strip shingles. For example, if the slots are cut in the raw felt before the felt is saturated with asphalt or other waterproofing material, the portions thus cut from 20 the sheet may be returned to the beater, thus saving a very considerable amount of valuable material which otherwise could not be economically reclaimed. It is also possible to form the sheet with slots on a paper-making 25 machine, thus avoiding the necessity of cutting the slots in the sheet of felt and returning the cut-out portions to the beater. There have been, however, serious practical objections to this general procedure in the 30 manufacture of strip shingles, one of which being the fact that during the operations of saturating, coating and cooling the sheet, local expansion or contraction is liable to occur and no way has 35 yet been discovered to control such aberrations in the length of the sheet. As a result of this behavior of the sheet, the transverse rows of slots in a sheet which may have been accurately spaced in the raw felt, 40 are very liable to be unevenly spaced longitudinally of the sheet by the time the sheet has reached the point where it is ready for cutting up into strip shingles. As these errors are often cumulative for considerable 45 stretches of the sheet, it is obvious that without compensating mechanism the cutter will sooner or later fail to strike the sheet on the desired transverse lines which are either across the ends or middles of the transverse 50 rows of slots according to the arrangement

of the strip shingles in the sheet. The present invention relates to means for synchronizing the feeding and cutting of the sheet so that in case of expansion or contraction of the sheet during its treatment to change it from raw felt into finished roofing, the rate of feed or the rate of cutting will be automatically adjusted so that the cuts will come in their proper relation to the slots in the sheet. In accomplishing this result, I connect the feed rolls and cutter with a common drive, one of these being connected to the drive through a planetary gear transmission, a member of which is held for adjusting motion by which the relation between the feed rolls or cutter and the drive can be adjusted so that the cutter chops the sheet in accordance with the pattern of slots therein. The adjusting motion in the transmission gearing may be produced by hand, or, as shown 55 on the drawing, by a motor, the motor being preferably controlled by a commutator associated with the cutter and a make-and-break device responsive to the pattern of the sheet. 60

For a more complete understanding of the invention, reference is had to the following description and to the drawings, of which,—

Figure 1 is a diagrammatic representation in side elevation of mechanism embodying the invention.

Figure 2 is an end elevation of a portion of the mechanism illustrated in Figure 1.

Figure 3 is a wiring diagram of the electrical connections employed with the mechanism.

Figure 4 shows in perspective some of the elements indicated in Figure 3.

Figure 5 is an elevation, partly in section, of a portion of the apparatus showing the planetary transmission drive and means for adjusting it.

Figure 6 is a slightly modified form of an embodiment of the invention.

Referring to the drawings in detail, a sheet of finished roofing, preferably with successive series of transverse slots, is indicated at 10. This sheet may be fed as by a pair of rolls 11, 12 to a cutter 13, which may be revolved on an axis 14 and cooperates with a cutting lip 15. The feeding rolls and cutter 100

are preferably driven from a common source of power through a suitable belt or chain 16 which passes over a pulley or sprocket wheel 17 mounted on a shaft 18. On the same shaft 5 may be mounted a pinion 19 which meshes with a gear 20 mounted on the shaft 14 and thus driving the cutter 13. On the shaft 18 a sprocket wheel 21 may also be mounted, this sprocket wheel being connected to a similar 10 wheel 22 as by a suitable chain 23. The sprocket wheel 22 may be connected to drive a shaft 24 through a variable speed-reducing unit 25 which may be adjusted to any desired ratio of speed reduction within its 15 limits. Such units may be obtained on the market and are of themselves not a part of this invention. Their purpose in this mechanism is to enable the operator to adjust the relative speeds of the cutter 13 and of the 20 feed rolls 11, 12 to accommodate strip shingles of different heights. The adjustment of such units during the operation of the machine is difficult so that for practical operation a further speed-changing device is necessary to facilitate the proper adjustments of 25 the sheet feed during the operation of the machine. To this end, on the shaft 24 may be mounted a pinion 26 meshing with a series of planetary gears 27 which also mesh with a 30 gear ring 28 provided with teeth on its inner face and another series of teeth on its outer face to mesh with a suitable worm 29 mounted on a shaft 30. The planet gears 27 are mounted on the arms 31 of a suitable 35 spider which is carried by a shaft 32, this shaft being connected to a sprocket wheel 33 which in turn is connected as by a chain 34 to another sprocket wheel 35 by which the feed rolls 11, 12, may be driven. As the 40 shaft 24 rotates with the pinion 26, the planet gears 27 are driven around the pinion 26 at a constant speed, the ring 28 being held stationary. The motion of the planet gears 27 causes a rotation of the shaft 32 which is 45 transmitted to the rolls 11, 12 by the connections hereinbefore mentioned. Since the cutter 13 and the feed rolls 11 and 12 are thus operatively connected, they rotate in a definite relation one to the other. This relation 50 may be slightly altered in either direction and to any desired degree by rotatably adjusting the gear ring 28. In this way, the sheet may be advanced or retarded as desired with respect to the cutter 13. To this end, 55 means are provided for rotating the shaft 30 in a suitable direction to shift the sheet with reference to the cutter so as to keep the cutter timed correctly with reference to the slots or other pattern on the sheet. The shaft 30 60 may be operatively connected to a suitable electric motor 36 as by a driving chain 37 and sprocket wheels 38, 39. In order to cause the motor to operate when necessary in the correct direction, a commutator is associated 65 with the shaft 14 and may comprise a pair of

fixed plates 40, 41 which may be successively engaged by a sliding contact member 42 which is mounted to revolve with the shaft 14. The revolving contact member 42 is preferably connected by a suitable wire 43 with a contact point 44 which is positioned to operate with another point 45 carried by a suitable lever 46 on which is mounted a feeler or roll 47 traveling on the surface of the sheet 10 of roofing material. The roll or feeler 47 is positioned so as to drop into one of the slots 48 in each transverse series in the sheet. While for convenience the term "slots" is used in referring to the pattern-forming elements of the sheet, this term as used in the specification and claims is intended to describe and cover any indentations or depressions in the sheet which would function in a similar manner with the feeler 47. When the roll 47 is in the slot 48, the contacts 44, 45 are together. If the cutter 13 is properly synchronized with the feed of the sheet, the contact member 42 will be out of engagement with the plates 40 and 41 while the points 44, 45 are together. That is, as the contact arm 42 is revolved in a counter-clockwise direction as illustrated in Figure 3, it leaves the plate 41 just before the roller 47 drops into a slot 48, closing the contact 44, 45. As the arm 42 swings around to come in contact with the plate 40, the roller 47 rises from the further end of the slot 48, opening the contact 44, 45 just before the arm 42 reaches the plate 40. The plates 40, 41 and the contact point 45 are connected to the motor 36 in such a way that if the arm 42 is in contact with the plate 41 while the contact 44, 45 is closed, the motor is rotated in one direction, while if the arm 42 is in contact with the plate 40 and the contact 44, 45 is closed, the motor is operated in the other direction. Since ordinarily a momentary closing of a circuit through the motor would not be of sufficient duration to overcome the inertia of the motor armature, the wires from the contacts 40, 41, 45 may be connected to the motor through a relay device such as is diagrammatically indicated in Figure 3, by which a momentary closing of a circuit through the contacts 44, 45 will result in a predetermined amount of rotation of the motor in one direction or the other, the relay device of itself being no part of this invention. The relay device as illustrated on the drawing is connected to supply lines 49, 50 and comprises a commutator wheel 51 which is suitably connected by reducing gears to the motor 36. The wheel 51 is preferably of insulating material on the periphery of which is secured a metal plate or ring as shown in Figure 4, which forms a pair of switches 52 and 53 with sliding contacts engaged therewith. When the motor 36 is at rest, the wheel 51 is normally in such a position that the switch 52 is closed and the switch 55 60 65 70 75 80 85 90 95 100 105 110 115 120 125 130

53 is open, these positions being diagrammatically indicated in Figure 3. The wheel 51 is suitably proportioned and is geared to the motor 36 in such a way that during a single 5 revolution of the wheel, the sheet feed will be adjusted a unit distance in one direction or the other. Cooperating with the wheel 51 are a number of relays conventionally indicated in Figure 3, the coils of the relays being 10 respectively designated as 54, 55, 56, 57, 58, and 59. The switch-operating armatures actuated by the various coils are indicated by corresponding reference characters, 54a, etc. These characters will also be used in the 15 description to indicate the switches operated by the armatures. The operation of the device is as follows:

Assuming the motor 36 to be at rest, the switch 52 closed, and the switch 53 open, suppose that the contact 44, 45 is made before the arm 42 leaves the plate 41, thus momentarily closing the circuit through the latter. Since the switch 52 is closed, this connects the feed wires 49, 50 through the relay coil 25 54 which being thus energized closes the switches 54a and 54b. The closing of the switch 54a maintains this circuit through the relay 54 when the contacts 41, 42 separate an instant later. The closing of the switch 30 54b energizes the relay 56, closing the switches 56a and 56b, and opening the normally closed switch 56c. The closing of the switch 56b energizes the relay 58 which closes the switch 58a and causes the motor 36 to run, 35 thus adjusting the feed of the sheet 10 and turning the commutator wheel 51. The latter results in the closing of the switch 53 and the opening of the switch 52 a moment thereafter. When the switch 52 opens, the relay 54 40 is deenergized and the switches 54a and 54b open. Since, however, the switches 53 and 56a have previously been closed, the relay 56 remains energized and the motor 36 continues to run. The opening of the normally closed 45 switch 56c prevents the possibility of energization of the relay 55 (which connects the motor for reverse operation) while the motor is running ahead under the control of the relay 56. When the wheel 51 has nearly completed a revolution, the switch 52 closes and the switch 53 opens. As the switch 54a is now open, the closing of the switch 52 does not energize the relay 54. The subsequent opening of the switch 53 breaks the circuit through 55 the relay 56, restoring all the relays to their normal positions as shown in Figure 3 and shutting off the current to the motor 36. In like manner, if the contacts 44, 45 are still together when the arm 42 reaches the plate 60 40, a momentary connection is made through the relay 55, thus closing the switches 55a and 55b. The latter energizes the relay 57 which in turn energizes the relay 59a and starts the motor in reverse direction. The 65 cooperation of the relays 55, 57, 59 with the

commutator 51 for reverse operation of the motor 36 is similar to that described for the forward operation of the motor.

It is thus apparent that if the sheet of roofing should begin to expand longitudinally 70 during the steps of treatment, the distances between successive series of slots 48 would be slightly greater than normal, consequently there would be a tendency of the slots to lag. This would result in the roller 47 being late in entering and leaving the slots. Such lateness would result in the arm 42 reaching the plate 40 before the contact 44, 45 was broken and thus energizing the motor 36 in a suitable direction to turn the shaft 30 and the ring gear 28 in such a way as to advance the sheet with reference to the cutter a suitable amount to bring the cuts on the proper lines. Conversely, a shrinkage of the sheet would shorten the distances between successive 80 series of slots and would thus cause the roller to fall into the slots 48 and close the contact 44, 45 before the arm 42 left the plate 41. Hence the motor 36 would be operated a predetermined amount through the relay system 85 49 to retard the sheet and bring the cuts on the correct lines.

Instead of regulating the feed of the sheet to conform to a uniformly rotating cutter, the speed of the sheet may be kept constant 95 and the cutter 13 adjusted. To this end, apparatus may be arranged as shown in Figure 5, the parts of the apparatus and the function of it being the same as for the adjustment of the feed, the motor 36 in this case 100 being employed to vary the angular position of the cutter 13 with respect to the advancing sheet and by advancing or retarding such angular position to maintain the cuts on the proper lines.

Having thus described certain embodiments of my invention, it should be evident to those skilled in the art that various changes and modifications might be made therein without departing from its spirit 110 or scope as defined by the appended claims.

I claim:—

1. Mechanism of the class described, comprising means for feeding a sheet having a recurrent pattern thereon, means for successively cutting off pieces from the end of the fed sheet, the cuts having a predetermined relation to the recurrent pattern, common means for driving said feeding and cutting means, and means for regulating the feed of the sheet to maintain said relation between the cuts on the sheet and the pattern, said regulating means comprising an electric commutator driven in synchronism with said cutter, a make-and-break device in series with said commutator intermittently actuated by the pattern on the sheet, means operatively connecting the feeding means with the driving means and adjustable to advance and retard the feeding means with respect to the 120 125 130

driving means during the operation of the mechanism, means for adjusting said connecting means, an electric motor for actuating said adjusting means, and means electrically connected to said motor, to said make-and-break device and to said commutator for causing the motor to effect a predetermined amount of adjustment of the feeding of the sheet relative to the operation of the cutter when a circuit is closed through said make-and-break device and said commutator.

2. Mechanism of the class described, comprising rolls for feeding a sheet having a recurrent pattern including a row of slots therein alined longitudinally of the sheet and substantially uniformly spaced, means for cutting the sheet successively with cuts having a uniform relation to the successive slots, common driving means for said feed rolls and cutter, and means for automatically compensating for slight variations in the spacing between successive slots and thereby maintaining the uniform relation between the cuts and slots, said automatic means comprising a feeler mounted to engage the sheet and to enter the successive slots, a commutator operatively connected with said cutter and normally synchronized with the feeling motion of said feeler, an adjustable driving connection between said driving means and said feed rolls, and means automatically actuatable upon a variation of the relation between the feeling motion and the cutting motion to adjust said driving connection in a direction to restore the normal synchronism of the feeler and cutter.

3. Mechanism of the class described comprising means for feeding a continuous sheet having a recurring pattern thereon, means for cutting successive pieces from the end of said sheet by cuts having a special relation to said pattern, common means for driving said feeding and cutting means, means for adjusting the operative relation between said feeding means and cutting means, and means for automatically controlling said adjustment, said controlling means including an electric circuit containing a pair of make-and-break devices and a feeler responsive to said pattern to actuate one of said devices, the other said device being actuated by said cutting means.

4. Mechanism of the class described comprising means for feeding a continuous sheet having a recurring pattern thereon, means for cutting successive pieces from the end of said sheet, driving means operatively connecting said feeding means and cutting means with each other and with a common source of power, and a variable speed transmission device and a synchronizing device interposed in said driving means between said feeding means and said cutting means, said transmission device being adjustable to any speed ratio within its range, said synchronizing de-

vice comprising means for automatically varying the relation of the feeding and cutting means for adjusting the pattern on the moving sheet with reference to said cutting means.

In testimony whereof I have affixed my signature.
